US00D932490S

(12) **United States Design Patent** (10) **Patent No.:** **US D932,490 S**
(45) **Date of Patent:** **** Oct. 5, 2021**

(54) **CARD READER DEVICE**

(71) Applicant: **Square, Inc.**, San Francisco, CA (US)

(72) Inventors: **Jeremy Martin**, San Francisco, CA (US); **Mani Razaghi**, San Francisco, CA (US); **Joseph Laucks**, San Francisco, CA (US)

(73) Assignee: **Square, Inc.**, San Francisco, CA (US)

(**) Term: **15 Years**

(21) Appl. No.: **29/762,013**

(22) Filed: **Dec. 14, 2020**

Related U.S. Application Data

(62) Division of application No. 29/657,827, filed on Jul. 25, 2018, now Pat. No. Des. 905,059.

(57) **CLAIM**

The ornamental design for a card reader device, as shown and described.

DESCRIPTION

FIG. 1 is a front perspective view of a card reader device; FIG. 2 is a front view thereof;

FIG. 3 is a back view thereof;

FIG. 4 is a left-side view thereof;

FIG. 5 is a right-side view thereof;

FIG. 6 is a top view thereof; and,

FIG. 7 is a bottom view thereof.

The dashed broken lines depict portions of the card reader device that form no part of the claimed design.

1 Claim, 7 Drawing Sheets
